CLAIM

The ornamental design for a cabinet lock, as shown and described.

DESCRIPTION

FIG. 1 is a perspective view of a cabinet lock showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of another state of the cabinet lock thereof; and,

FIG. 9 is a perspective view of further another state of the cabinet lock thereof.

The broken lines shown in the drawings depict portions of the cabinet lock in which the design is embodied that form no part of the claimed design.
